CLAIM

The ornamental design for an eyeglasses component, as shown and described.

DESCRIPTION

FIG. 1 is a front view of an eyeglasses component showing an embodiment of the claimed design;

FIG. 2 is a rear view thereof;

FIG. 3 is a right side view thereof, the left side being a mirror image thereof;

FIG. 4 is a top view thereof;

FIG. 5 is a bottom view thereof;

FIG. 6 is a front view of an eyeglasses component showing an alternate embodiment of the claimed design;

FIG. 7 is a rear view thereof;

FIG. 8 is a right side view thereof, the left side being a mirror image thereof;

FIG. 9 is a top view thereof; and,

FIG. 10 is a bottom view thereof.

The dashed broken lines in the figures show portions of the eyeglasses component that form no part of the claimed design.

The dot-dash broken lines in the figures show boundaries that form no part of the claimed design.

1 Claim, 6 Drawing Sheets
